CLAIM

The ornamental design of a wipes dispenser, as shown and described.

DESCRIPTION

FIG. 1 is a top, front perspective view of a wipes dispenser in accordance with our new design;

FIG. 2 is a bottom, rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings depict portions of the wipes dispenser that form no part of the claim.
